UNITED STATES PATENT OFFICE.

EDWARD F. McGEE, OF CHIPLEY, GEORGIA.

AUXILIARY CAR-STEP.

1,120,958.

Specification of Letters Patent. Patented Dec. 15, 1914.

Application filed May 13, 1914. Serial No. 838,366.

To all whom it may concern:

Be it known that I, EDWARD F. McGEE, a citizen of the United States, residing at Chipley, in the county of Harris, State of Georgia, have invented certain new and useful Improvements in Auxiliary Car-Steps; and I do hereby declare the following to be a full, clear, and exact description of the invention, such as will enable others skilled in the art to which it appertains to make and use the same.

This invention relates to improvements in car steps, and particularly to folding extensions steps.

The principal object of the invention is to provide a simple and novel device of this character whereby an extra lower step can be quickly and easily extended for use, or folded up under the bottom step of the car out of the way.

Another object is to provide a device of this character which is not only simple in construction, but which may be quickly and easily applied to cars now in use without radical modifications to the car step.

Other objects and advantages will be apparent from the following description, when taken in connection with the accompanying drawings.

In the drawings: Figure 1 is a front elevation of a flight of car steps showing my invention in operation. Fig. 2 is a similar view showing the auxiliary step in folded position. Fig. 3 is a side elevation of the step showing the auxiliary step in extended position. Fig. 4 is a vertical section on the line 4—4 of Fig. 3. Fig. 5 is a side elevation of the step showing the auxiliary step in folded position. Fig. 6 is a top plan view of the step showing the auxiliary step in folded position.

Referring particularly to the accompanying drawing, 10 represents the side rails or boards and 11 the treads of a flight of steps of a railway coach, in connection with which my invention is particularly adapted for use. Mounted on each of the sideboards is a metal plate 12 which extends forwardly beyond the front edge of the side board. Formed through each of these plates are the rearwardly extending and parallel slots 13 and 14, said slots inclining slightly toward the rear, and terminating at the rear, in the notches 15. Communicating with the forward end of each of the slots 13 and 14 is a vertical slot 16, the lower end of each of

which terminates in a rearwardly disposed notch 17. Disposed on the outer face of each of the plates is a vertical bar 18, each of which is provided with a pair of bolts or rivets 19 which extend through the slots 13 and 14, one end of each of the rivets being secured in the bar and having its other end provided with a head 20 engaging against the inner face of the plate at the sides of the slot. Carried by the lower ends of the bars 18 are the angle plates 21 to which are secured the ends of the auxiliary step tread 22. Secured at their lower ends to the forward portions of the ends of the auxiliary tread are the vertically extending rods 23, each of which is provided with a rearwardly extending arm 24 secured at its rear end to the upper end of one of the bars 18. The upper portion of each of the rods 23 is formed with an offset portion 25 and has mounted thereon a hand grip 26. Connected at their rear ends to the rear upper portions of the side boards 10, and at their forward ends to the bars 18 are springs 27 which are under tension when the auxiliary tread is in extended position.

When the auxiliary step is in extended position the bolts or rivets 19 are disposed in the lower ends of the vertical slots 16, the said tread being below and forwardly of the lowermost step of the ordinary flight. To fold the step, the hand grips 26 are grasped and the tread and bars 18 lifted vertically upward, until the bolts 19 are opposite the forward ends of the slots 13 and 14. The springs will then pull rearwardly on the bars 18 and cause the bolts to fly back to the rear ends of the said slots and dispose the tread 22 beneath the lowermost step of the flight. To extend the step the handles are grasped, the bars pulled forwardly, until the bolts are disposed in the vertical slots and then the tread pushed straight downward.

What is claimed is:

1. The combination with the steps of a railway coach, of members mounted on the sides thereof, said members being provided with vertical slots in the forward portions thereof, rearwardly extending slots communicating therewith, a frame carrying means slidably disposed in the slots and arranged for vertical and horizontal movement, resilient means between the frame and the coach steps, a step tread carried by the frame, and handle members connected to the said tread and to the upper portion of the

frame, whereby the frame can be manipulated to move the said tread into and out of operative position.

2. The combination with the steps of a railway coach, of a frame mounted on a portion of the steps for vertical and horizontal movement, an auxiliary step carried by the frame, and means for automatically moving

the frame horizontally in one direction when said frame has been moved vertically. 10

In testimony whereof, I affix my signature, in the presence of two witnesses.

EDWARD F. McGEE.
